UNITED STATES PATENT OFFICE.

ERNEST C. OAKES, OF BLOOMFIELD, NEW JERSEY, ASSIGNOR, BY MESNE ASSIGNMENTS, TO EMPIRE MILKING MACHINE COMPANY, INC., OF ROCHESTER, NEW YORK, A CORPORATION OF NEW YORK.

VACUUM PUMP VALVE.

Application filed October 28, 1922. Serial No. 597,471.

The invention relates to vacuum pumps and particularly to the valve arrangement, mechanism and its specific construction, for the particular objects of producing an efficient vacuum pump and which under certain conditions may be substantially noiseless, and at the same time will be economical for manufacture in quantity and any wearing parts of which may be readily and economically replaced or repaired, and is a particular development for vacuum pumps involving the exacting requirements of a suction system used for mechanical vacuum milking machines.

15 The manufacture of a vacuum pump has heretofore involved special features of construction particularly with respect to the airtight joints and in that respect the valves. Such has more or less involved a 20 complete redesigning, or radical modifications in construction, and also expensive parts or expensive work for replacement and repair in the ordinary course of use.

25 While the general construction of vacuum pumps may be varied in many respects, the essential features to secure efficiency and other advantages, as well as replacement and repair in regular use, involve the valves for intake and exhaust and facility of their 30 adjustment or replacement. The difference between success and failure of a vacuum pump depends or hinges upon the efficiency of the valves and the facility for their replacement and repair.

35 While various modifications may be made in my invention, a particular embodiment of one form of construction is shown in the accompanying drawings in which:

40 Fig. 1 is a vertical elevation, fragmentary in section, to show the base and valves.

Fig. 2 is a vertical section of the axis of a piston, showing, on a large scale, a piston valve.

45 Fig. 3 is a bottom view of the piston valve-plug.

Fig. 4 is a plan of the pump base with the pump cylinders in section on the line 4—4, Fig. 1.

50 Fig. 5 is a plan view of the combined piston-head valves and gasket.

The pump 1 has cylinders 2—2 with pistons 3—3, crank-shaft 4, bearings 5. A pulley 6 secured to one end of the crank-shaft 4 indicates a means of turning the crank-

shaft, although other suitable power delivery may involve many forms, as, for example, an internal combustion engine, direct coupled with the crank-shaft or direct coupled to the air cylinders, will serve to actuate the pistons 3—3 to perform their function in pumping a vacuum.

The base 7 has a vacuum port 8 leading to the vacuum pipes or tubes which constitute the system in which a vacuum is desired,—as, for example, a system for 65 milking machines, the preferred form of which today involves a suction and for which vacuum piping is provided in order to create the suction at the milk pails and at the 70 teat cups, controlled by a suitable pulsating mechanism, in order to establish the periodic pulsating or milking effect, in conjunction with the suction draining from the cow teat into the milk pail. For this purpose it must be understood that the successful operation of vacuum milking depends upon 75 substantially uniform suction, therefore vacuum, and for this purpose a vacuum pump meeting the exacting requirements is 80 essential and involves the major feature of successful mechanical milking machines.

The vacuum outlet 8 connects with the ports 9—9 which surround pedestals 10—10, and have superposed thereon a gasket 11 which has flaps 12—12 formed by a circular 85 annular slot cut into the gasket sheet 11. Thus the gasket sheet 11 determines the proximity of the cylinders 2—2 to the base 7, and likewise the limit of approach of pistons 3—3 to the base, so that upon the 90 assembly and mounting of the cylinders or pump casing 1 upon the base 7, the relation and registering of the cylinder-heads with the base, and the valve mechanism, becomes a matter of certainty without any specific 95 adjustment or trial. It will be noted that the flap 12 for a substantial part of its circumference, as at 13, is integral with the sheathing forming the gasket, as, for example, gasket material known as vellumoid, 100 which is very effective as a gasket and at the same time provides toughness and tenacity to constitute what may be called a hinge at 13—13. This permits the periodic slight rise of the flaps 12—12 from their respective 105 seats 14, about their periphery and the top of the pedestal 10 in the centre of the port 9, and at the same time supplies sufficient

strength and toughness to bridge the annular port space 9 and produce an air-tight joint.

In the end of the pistons 3—3 an opening 5 is threaded to provide for a plug 15, which plug screws into the piston-head with threads 16 and has openings 17—17 providing air-ports in said plug 15 in conjunction with a valve. The valve in the piston-head 10 comprises a valve washer 17^a with a thin metal sheet 18, both riding on a stud screw 19 screwed into the plug with a head 19^a with which the disc 18 engages in order to limit its movement. This disc 18 is made 15 very light and is sealed to the sheet or disc 17^a so that both move up and down together, thereby forming the valve packing on the top surface or valve seat 20 surrounding the ports 17—17. 20 By the use of a plug containing all the outlet valve mechanism at the end of the piston 3, a flush piston end is provided, with a minimum of clearance so that the vacuum operation in pumping is extremely effective 25 and efficient, while at the same time the plug 15 being slightly less in diameter than the periphery 12^a of the valve flap 12 on the base, covering the ports 9, the approach of the pistons 3—3 to the end of their downward stroke insures the reseating of the valve flap 12 upon the base.

It will thus be seen that the valve mechanism involved in this invention comprises a very simple and efficient piston plug for exhausting the air from the cylinder through the piston-head, and an extremely simple air valve on the base to permit the drawing of air out of the vacuum ports 9—9 and the vacuum line or pipe connection 8. The removal of the base 7 from the cylinder-heads by means of lag bolts 7^a—7^a, provides immediate access to the base valve as well as the gasket to assure air-tightness of the cylinder-heads with the base, and also assures a ready access to the valve plugs in the vacuum pump pistons, whereupon the holes 17—17 in the valve plug permit, if desired, ready accessibility to the plugs as a hand-hold or tool-hold to unscrew them from the piston-heads with the facility for entire removal of the valve plugs from the piston-heads, so that the entire air valve mechanism of the pistons may be removed and replaced, or may be readily inspected for adjustment or repair.

It will thus be seen that the entire vacuum production mechanism in the vacuum pump, comprising the vacuum pipe port and a valve in each pump-piston head, involves extremely simple construction both as to manufacture as well as adjustment and repair. Essentially it involves a base air-intake valve, as an integral part of the gasket for the cylinder-heads, and a valve plug embodying a nicely adjusted relative weight of

washer and valve plate riding on a simple accessible stud,—while the relations of the valve plug in the piston end, in view of the particular relation thereof to the intake valve flap on the base, insure in their co-operation the certainty of operation with efficiency. The relation of parts also permits of the least possible clearance, so that besides the effectiveness, the efficiency of the vacuum pump is increased to a maximum. 75

On account of the light parts involved, and the very limited "play" of the valve flaps both in the intake and the piston-head outlet, a minimum condition of noise exists, and as the construction provides for the utilization of soft material and the avoidance of metallic contact between the valve seats and valves, the construction practically provides for an entirely noiseless operating construction. 85

In view of the special adaptation of this vacuum pump and its valve mechanism, the avoidance of noise in connection with a dairy or cow barns is obviously advantageous, and it is on that account that this invention involves a most efficacious vacuum pump for the particular purposes for which it is essentially intended, that is to actuate vacuum milking machines. 90

In the use of vacuum milking machines 95 no absolute vacuum is required, but in the most successful forms now in use about 17 inches of vacuum at the pump supplies the conditions in the vacuum system. With this approximately 17 inches of vacuum, however, a substantial amount of air must be moved, as, for example, the air necessary to produce the suction in the pails and the actuation of the pulsating mechanism which effects the milking at the teat cups, and it 100 may therefore be regarded, in a general way, that large volume with medium vacuum pressure is the condition prevailing for the milking machine installations. 105

As the actuation of the pulsators for the 110 teat cup operation, as well as the suction in the milk pails, must be continuous and above all must be substantially uniform, it will be seen that for successful milking it is essential that the vacuum pump be uniform in 115 operation and be thoroughly dependable because variations or failures lead in turn to serious trouble and damage or injury to the cows.

It will thus be seen that the various 120 particular requirements accomplished by the construction hereinbefore described and any modifications thereof, aim to accomplish the particular purposes which involve very exacting requirements.

While various modifications may be made without departing from the spirit of this invention,—what I claim and desire to secure by Letters Patent is:

1. An air pump comprising a pair of 130

cylinders, oppositely disposed pistons in said cylinders, a common base for said cylinders and a common gasket for both cylinders, an air inlet port centrally in each cylinder in the base, and a partially severed portion of the gasket above each inlet port adapted to provide an inlet valve flush with the entire surface of the cylinder head and on the approach of the piston to seat upon the base and close the inlet ports and form a spacer coincident with the cylinder-head clearance upon the piston reaching the outer end of its stroke, whereby said valve and gasket jointly form in closed position a cushioning engagement flush with the end and with minimum clearance from the piston when in extreme position.

2. In an air pump, duplex cylinders, a base therefor, a combined gasket and valve sheet between the cylinder-head and the base

adapted to provide a clearance sheathing an air-tight joint for the cylinder-head and having a partially severed central flap in each cylinder-head adapted for articulation as a valve cover functioning due to the flexibility of the material of the sheathing in combination with duplex pistons having integral ends flush with a removable piston valve cap and movable at the end of each stroke close to the base valve and gasket throughout the head of the cylinder, whereby a minimum clearance is provided with parts adapted to accommodate irregularities of movement without injury to the rigid portions of the piston.

In testimony whereof, I have signed my name to this application this 25 day of October, 1922.

ERNEST C. OAKES.
